LIFTER KNIFE FOR LOOM DOBBIES

Elbridge R. Holmes, Worcester, Mass., assignor
to Crompton & Knowles Loom Works, Worcester,
Mass., a corporation of Massachusetts

Application June 5, 1939, Serial No. 277,487

3 Claims. (Cl. 139—67)

This invention relates to improvements in loom dobbies and it is the general object of the invention to provide an improved lifter knife for the harness actuating hooks.

5 In the usual dobby the harness lifting hooks are adapted for cooperation with lifter knives which ordinarily reciprocate in opposite directions in spaced horizontal planes. Because of the requirement that the rear harness frames shall be lifted higher than the front frames, the rear end of the knife moves more than does the front end. When in one extreme position the knife will be oblique with respect to the hooks in one direction, while in the other extreme position the 10 knife will also be oblique but in the opposite direction. The position of the hooks is determined by so-called fingers which have direct engagement with the pattern mechanism, and the outer ends of these fingers are generally enlarged to provide counterbalance heads which 15 over-balance the hooks.

It is an important object of my present invention to strengthen the lifter knife by adding thereto a web or rib so constructed as to provide 20 additional strength more particularly in the center of the knife and arranged so that the rib avoids interference with the heads of the fingers when the knife assumes its oblique position nearest to the finger heads.

25 The aligned heads lie in a line perpendicular to the dobby side frames and form a triangle with the oblique knife when the latter is nearest the heads. I locate the reinforcing rib in this triangle and find that in doing so the web or rib 30 is wider at a point near the center of the knife than at the end, thereby giving the knife its greatest reinforcement at a point where the harness lifting strain is greatest, that is, farthest from the supporting links which support and drive 35 the knife.

Dobbies are made right and left hand and in order to provide a knife usable in both kinds of dobbies I form the rib widest at the central part 40 of the knife and taper it toward the ends. This 45 retains the greatest reinforcement near the middle of the knife while permitting either end to be at the rear part of the dobby.

With these and other objects in view which 50 will appear as the description proceeds, my invention resides in the combination and arrangement of the parts hereinafter described and set forth.

In the accompanying drawing, wherein a 55 convenient embodiment of my invention is set forth,

Fig. 1 is a rear elevation of a dobby equipped with my improved knife.

Fig. 2 is an end view taken in the direction of arrow 2, Fig. 1.

Fig. 3 is a vertical section on line 3—3, Fig. 2. 5

Fig. 4 is a diagrammatic plan view looking in the direction of arrows 4—4, Fig. 3 showing the knife adjacent to the fingers in extreme outward position.

Fig. 5 is an enlarged transverse section through 10 the central part of the knife, and

Fig. 6 is a perspective view of the improved knife.

Referring to Fig. 1, I have shown a loom frame 10 having two arches 11 on which is supported 15 the dobby designated generally at D. The dobby is provided with a plurality of harness lifting jacks 12 which are attached to the warp harnesses not shown. Each jack has pivoted thereto a dobby back lever 13 provided with top and bottom 20 hooks 14 and 15, respectively. The position of the hooks is determined by pattern fingers 16 which lie over a pattern chain 17 mounted on a cylinder 18. The fingers are normally supported by a cross bar 19 of the dobby and are raised by 25 pegs 20 on the pattern chain and fall to resting position on the support 19 when no peg is under them. The fingers are arranged in pairs, one member of each pair having an upstanding end 21 to have direct engagement with a lower hook 30 15, while the other finger of the pair has an end 22 connected by means of a vertical rod 23 to the top hook to position the latter. In order that the weight of the hooks and rods may be 35 counter-balanced each finger 16 is provided with 35 a counterweight head 24 which projects upwardly from the main body of the finger as indicated clearly in Fig. 3.

The dobby frame is formed with front and 40 back side plates 30 and 31 through which extends a rocker shaft 32 driven by a lever 33 keyed thereon behind plate 31 and having connection with a vertically reciprocating rod 34 driven by one of the loom shafts in well-known manner. Shaft 32 is extended beyond the side 45 plate 30 to have keyed thereto front lever 35, and these levers rock together with the shaft 32.

Lever 33 has a short upper arm 40 attached by connector 41 to one end of the upper knife 42, while upper arm 43 of the lever 35 is attached 50 by a connector 44 to the front part of knife 42. The side plates have laterally projecting arms 45 slotted as at 46 to afford sliding support for the top knife 42. It should be noted that the rear arm 40 is longer than the front arm 43, so 55

that for equal angular motions of the levers 33 and 35 the rear end of knife 42 will move farther than the front end thereof.

In similar manner, lever 35 has a depending short arm 52 driving a connector 53 while the rear lever 33 has a depending arm 50 longer than arm 52 and is attached to connector 51. Rods 51 and 53 correspond in function to the upper rods 41 and 44, respectively. The side plates of the dobby are provided with lower laterally extending arm 55 having horizontal slots 56 similar to the slots 46.

The matter thus far described is of common construction and of itself forms no part of my present invention. As the loom operates rod 34 is raised from one pick of the loom to move knife 42 outwardly or to the right as viewed in Fig. 1, while on the following pick rod 34 descends to move the knife 42 rearwardly or to the left. Opposite motions occur simultaneously with the bottom knife to be described. The hooks 14 and 15 will either engage or clear their respective knives, depending upon the control exercised over them by the pattern chain.

25 My present invention relates more particularly to the bottom knife, although the top knife 42 may if desired be formed to include the invention which I will now describe. The bottom knife K comprises an elongated body 60 at each end of 30 which is formed a slide bearing block 61. From the forward end of the knife K there projects a gudgeon 63 for cooperation with connector 53, while a second gudgeon 62 projects rearwardly from the back end of the knife for cooperation 35 with the connector 51. The knife K has a shoulder 64 defining a hook engaging lifter edge 65 of usual form for cooperation with the lower hook 15. The parts of knife K already described are of usual form, bearings 61 sliding in slots 56 40 as the knife reciprocates by rocking of shaft 34.

45 My invention relates more particularly to a reinforcement for the knife set forth for instance in Fig. 6 and includes a web or rib 70 integral with the knife body 60 and projecting to the right thereof below the lifter edge 65. The rib 70 is low enough to permit proper engagement of the lifter edge 65 with the bottom knives 15. The web is widest at a point midway between the blocks 61 and tapers off to a negligible width 50 near said blocks. By this construction the central part of the knife which is farthest removed from the gudgeons 62 and 63 is given additional strength to withstand the effort of lifting the harness frames.

55 Reference to Fig. 4 may be had to understand the relation between the reinforcing web and the previously described heads of the dobby fingers. In that figure the knife K is indicated in two positions, position I in dotted lines suggesting the angular relation of the knife with respect to the dobby sides when knife K is in its extreme in position or to the left as viewed in Fig. 1. Full line position II, on the other hand, indicates the position of the knife K when the latter is moved to its extreme outward position. It will be seen that position I is oblique with respect to the dobby sides with the rear end of the knife nearer the dobby back levers 60 65 70 75 than the front end, whereas in position II the knife is also oblique but with the rear end thereof farther from the dobby back levers 13 than the front end. This changing angular relation of the knife will be understood from the fact that the front and back arms of the driving levers

are of unequal lengths, the rear arms being longer.

The heads 24 of the fingers 16 are in substantial alignment transversely of the path of motion of the knife K and extend in a row which is more or less perpendicular to the sides 30 and 31. It will also be seen from Fig. 3 that these heads project upwardly beyond the plane in which lower knife K slides. It is this latter relationship which has an important bearing on 10 the shape of the reinforcing rib 70. It will be seen from Fig. 4 that when the knife is in position II the rear end thereof is close to the aligned heads 24, at the right hand side of Fig. 4, while the front end is spaced farther from said heads. 15 This relationship defines a triangle between the body 60 of the knife and the aligned heads 24. The rib 70 is located in this triangle, the rear end of the rib being of slight or negligible width near the vertex of the aforesaid triangle, and 20 the wider central portion of the rib lying in that part of the triangle approximately midway between the side plates 30 and 31. By this arrangement the knife is made strongest at its longitudinal center which is farthest removed 25 from the driving links or connectors 51 and 53. The outer edge 75 of the rib near the rear part of the row of aligned heads 24 may be uniformly spaced from the latter, although this is not a necessary relation. 30

During operation of the dobby the knife K will start on its outward motion from the dotted position I, Fig. 4, in engagement with any hooks which might have been left in low position by the pattern chain. During this outward motion 35 the knife will change its angular relation with respect to the dobby sides and ultimately reach the position II, where it is nearest the aligned head 24. During this outward motion the knife K will be subject to the strain of lifting the 40 harness frames not shown which correspond to the hooks engaged thereby.

As previously stated, dobbies are made right and left hand and in order that the knife set forth herein may be usable in dobbies of both hands 45 I make the reinforcing rib symmetrical so that its ends taper toward the body 60 at points adjacent to the sliding blocks 61 with the widest part of the rib at or near the longitudinal center of the body 60. By so forming the rib I provide 50 a knife which is evenly balanced and wherein the amount of reinforcement added by the rib diminishes from the center toward the ends. For use in any given dobby, however, it is sufficient if one end only of the knife is made with 55 the web formed as described and I do not wish to be limited in the practice of my invention to a rib which is necessarily symmetrical about a central transverse axis of the knife.

From the foregoing it will be seen that I have 60 provided an improved dobby knife having a reinforcing rib which is located between the body of the knife and the finger heads 24 when the knife is in its outermost position II, Fig. 4. Such a construction provides maximum reinforcement for the central part of the knife most distant from the supporting gudgeons 62 and 63. It will 65 also be seen that the reinforcement can be shaped so that the knife can be used in both right and left hand dobbies. Furthermore, the upper knife can be the same as knife K if desired. The lifting strain on the knife places a compression strain on the rib and the latter can therefore be made comparatively small while at the same 70 75 75

time adding considerably to the strength of the dobby.

Having thus described my invention it will be seen that changes and modifications may be made therein by those skilled in the art without departing from the spirit and scope of the invention and I do not wish to be limited to the details herein disclosed, but what I claim is:

1. In a dobby having a set of fingers with heads aligned transversely of the dobby, a reciprocating knife movable toward and from the heads along a path which when projected passes through the heads, an elongated body forming part of the knife and having a hook lifting edge, means to move the knife on a working stroke toward said heads and place one end of the lifting edge nearer said heads than the other end of said lifting edge at the conclusion of a working stroke to locate the lifting edge diagonally with respect to the aligned heads, and a reinforcing rib on said body below the lifting edge and projecting from the body toward the aligned heads and located between the latter and the body when the knife is nearest said heads, said rib being narrow at a point adjacent to one end of said lifting edge where the body is near the heads and wider at a point near the longitudinal center of the lifting edge where the body is farther from said heads when the knife is nearest said heads at the end of a working stroke.
2. In a loom dobby, a reciprocating hook engaging knife movable in a given plane, means to move the rear end of the knife through a greater distance than that through which the front end of the knife moves, a set of dobby fingers having heads projecting across the plane in which the knife reciprocates and aligned in a direction transverse of the direction in which the knife moves, said knife having an elongated body provided with a hook lifting edge, said means moving the knife toward the heads to a position diagonal with respect to the aligned heads, and a reinforcing rib projecting from the body below the edge and toward the heads, said rib being of negligible width near the rear end of the knife and being of greater width at a point near the longitudinal center of the knife and extending into the space between the heads and the knife.
3. In a loom dobby, a reciprocating hook engaging knife movable in a given plane, means to move the rear end of the knife through a greater distance than that through which the front end of the knife moves, a set of dobby fingers having heads projecting across the plane in which the knife reciprocates and aligned in a direction transverse of the direction in which the knife moves, said knife and aligned heads forming a triangle the rear part of which is comparatively narrow and that part thereof adjacent to the longitudinal center of the knife being wider than the rear part of the triangle when the knife is nearest to the heads, said knife having a body with an upper hook engaging edge and a rib to reinforce the body projecting from the latter at a point below the lifting edge and extending into the triangle, said rib being of less width near the narrow end of the triangle than at a point where the triangle is wider.

ELBRIDGE R. HOLMES. 35
